WIRE JOINT

William F. Richardson, Carthage, Mo., assignor to Flex-O-Lators, Inc., Carthage, Mo., a corporation of Missouri

Application September 26, 1955, Serial No. 536,591

2 Claims. (Cl. 287—49)

This invention relates to new and useful improvements in wire joints, and has particular relation to joints wherein it is desired to connect firmly together a pair of wires in intersecting relationship.

The principal object of the present invention is the provision of a joint of the character described which secures the two wires together in such a manner that they are prevented positively from moving longitudinally relative to each other, and also so that they cannot tilt relative to each other, or twist or turn axially. The joint as shown is intended primarily for connecting wires together in and around the spring assemblies of furniture upholstery, but it will be apparent that the inventive concepts involved have an application to wires or rods generally.

Another object is the provision of a wire joint of the class described which is economical and extremely simple, the only piece used in addition to the wires themselves being a simple clip which may be easily formed of strip metal.

Other objects are efficiency and dependability of operation, adaptability to function efficiently even if the clip should work loose due to repeated flexing, adaptability to hold the connected wires in any desired angular relation, and adaptability to join wires of unequal sizes.

With these objects in view, as well as other objects which will appear in the course of the specification, reference will be had to the drawing, wherein:

Fig. 1 is a face view of a wire joint embodying the present invention, taken at right angles to the general plane in which the two wires are positioned,

Fig. 2 is a sectional view taken on line II—II of Fig. 1, and

Fig. 3 is an enlarged sectional view taken on line III—III of Fig. 1.

Like reference numerals apply to similar parts throughout the several views, and the numerals 2 and 4 apply respectively to the two wires to be joined. The wires are illustrated as unequal in diameter to demonstrate that the joint is applicable to join wires of different sizes, but it will be apparent that the wires could be of equal size if desired. One of the wires, usually the heavier wire 2 if the wires are unequal, is crimped at 6, at right angles to the final plane of the two wires. The depth of the crimp, on its concave side, is equal to the diameter of wire 4. Wire 4 has a relatively elongated bight 8 formed therein and extending at right angles to the general run of the wire. Said bight has generally parallel side reaches 10 and a connecting portion 12.

The wires are laid together as shown, with the connecting portion 12 of bight 8 lying in crimp 6 of wire 2, and with the parallel side reaches 10 lying parallel to and substantially against wire 2 directly adjacent crimp 6.

2

A sheet metal clip 14 is then clamped about reaches 10 of wire 4 and the coextensive portion of wire 2. As shown in Fig. 3, the upper edges of both wires lie in a single plane. This relationship is provided by forming the depth of crimp 6 equal to the diameter of wire 4, and by the use of a special clamping tool, forming no part of the present invention, which holds the wires in the relationship shown in Fig. 3 as clip 14 is drawn tight. This coplanar relation of the wires at the upper surface of the joint is especially useful where a large number of mutually right-angled wires are to be joined to form a wire fabric or mesh for supporting padding or the like in upholstery work, since it presents a smoother supporting surface.

This joint is deemed to have numerous advantages. It is easily and economically formed. It lends itself well to the accurate assembly, by a customer, of pre-formed parts, since the crimping 6 and bights 8 can be machine-formed by the manufacturer. Each wire is positively locked against longitudinal movement relative to the other wire, against rotation around its own axis, and against tilting around the axis of the other wire. These relationships are maintained even though clip 14 may enlarge and loosen due to repeated and continuous stresses on the joint, so long as portion 12 of wire 4 is retained in crimp 6 of wire 2. It is quiet, reducing to a minimum the rubbing or grinding noises so objectionable in upholstery and other applications. It lends itself very well to the holding of the wires at substantially any desired angle simply by forming bight 8 to project at any desired angle from the general run of wire 4. The holding power and rigidity of the connection is enhanced by the formation of clip 14 with an axial length substantially greater, preferably at least two or three times greater, than the diameter of the wires to be joined. This prevents any angling between wire 2 and reaches 10 of wire 4.

While I have shown and described a specific embodiment of my invention, it will be apparent that many minor changes of structure and operation could be made without departing from the spirit of the invention as defined by the scope of the appended claims.

What I claim as new and desire to protect by Letters Patent is:

- 45 1. A wire joint comprising a first wire crimped at a point to form an indentation therein, a second wire disposed angularly to said first wire and extending through the indentation thereof, said second wire being transversely offset adjacent said first wire and having the connecting portions at said offset lying against and parallel to said first wire, and means rigidly joining said first wire and the connecting portions of said second wire.
- 50 2. A wire joint comprising a first wire crimped at a point to form an indentation therein, a second wire disposed angularly to said first wire and extending through the indentation thereof, said second wire being transversely offset adjacent said first wire and having the connecting portions at said offset lying against and parallel to said first wire, and a clip encircling and clampingly joining together said first wire and the connecting portions of said second wire.
